UNITED STATES PATENT OFFICE.

WILLIAM HENRY FAUBER, OF CHICAGO, ILLINOIS.

ENGINE.

1,181,070.

Specification of Letters Patent. Patented Apr. 25, 1916.

Application filed December 9, 1912. Serial No. 735,839.

To all whom it may concern:

Be it known that I, WILLIAM HENRY FAUBER, a citizen of the United States, and a resident of Chicago, in the county of Cook 5 and State of Illinois, have invented certain new and useful Improvements in Engines; and I do hereby declare that the following is a full, clear, and exact description thereof, reference being had to the accompanying drawings, and to the letters of reference 10 marked thereon, which form a part of this specification.

This invention relates to valves for controlling the admission or exhaust of fluid 15 to or from a space or chamber subject to fluid pressure, such as the cylinder of an engine, pump, compressor or the like.

My invention includes features of construction applicable to valves, the movable 20 member of which has either rotative, oscillating or reciprocatory movement, but some of the features of construction are more particularly applicable to valves of that kind embracing a valve casing having a cylindric 25 valve chamber and a cylindric valve member having bearing in such valve chamber and which is turned or rotated therein for opening and closing a port or ports in said chamber, and still other features of the invention are especially applicable to rotative 30 valves used in connection with internal combustion engines.

Among the objects of the invention are to provide improved features of construction, 35 in valves used for the purposes stated, whereby the pressure existing within the cylinder and tending to lift the movable member of the valve from its seat will be opposed or counteracted by means operated 40 by the pressure within the cylinder and acting on said valve member in a direction to press the same toward its seat.

Other objects of the invention are to improve the construction of such valves in 45 other respects, as will hereinafter appear.

The several features constituting my invention are illustrated in the accompanying drawings embodied in a four-cylinder, internal combustion engine having reciprocating 50 pistons, but it is to be understood that the principal features of the invention may be applied to rotary as well as reciprocating engines, and to pumps or compressors as well as to engines. And, so far as adapted 55 only for use in connection with internal

combustion engines, the features of my invention may be applied to engines of other forms than that shown.

The invention consists in the matters hereinafter described and pointed out in the appended claims.

In the accompanying drawings—Figure 1 is a view in side elevation of the upper ends of the four connected cylinders of a multi-cylinder engine and a valve casing common 65 to all of the said cylinders; Fig. 2 is a plan view of the parts shown in Fig. 1; Fig. 3 is a view in side elevation of the entire engine shown in Figs. 1 and 2, with a valve casing and adjacent parts, shown in vertical, 70 longitudinal section; Fig. 3^a is a fragmentary view in elevation showing the connection between the valve gear-case supporting standard and the crank case. Fig. 4 is an enlarged, detail cross section of the valve 75 casing, taken on line 4—4 of Fig. 2; Fig. 5 is a sectional view, taken on line 5—5 of Fig. 2, showing in end view the valve casing and associated parts; Fig. 6 is a detail, horizontal section through the part of the valve 80 casing and valve member associated with one of the cylinders, showing a modified construction of the same; Fig. 7 is a face view of the cylindric valve member shown in Fig. 6; Fig. 8 is a detail sectional view of the auxiliary cylinder and the piston 85 therein, showing the said piston partially in elevation and partially in section; Fig. 9 is a view of the packing ring, shown in Fig. 8; Fig. 10 is an end view of the piston shown in Fig. 8 with parts in section; Fig. 11 is a plan view of a part of the valve casing and bearing block, illustrating a different construction in means for applying pressure to 90 said block; Fig. 12 is a sectional view, taken on line 11—11 of Fig. 11; Fig. 13 is a detail section, taken upon line 12—12 of Fig. 11; Fig. 14 is a detail section corresponding 95 with the upper part of Fig. 12, showing still another form of device for applying pressure to the movable bearing block; Fig. 15 is a plan view of the parts shown in Fig. 14.

The engine shown in the accompanying drawing is an internal combustion or explosive engine and is provided with four upright power cylinders 5, 6, 7 and 8, arranged side by side and attached at their lower ends to a crank case 9, common to all of the cylinders. The cylinders are provided with pistons 5^a, 6^a, 7^a, and 8^a, which have opera- 105

tive connection in the usual manner with a crank shaft 10, mounted in the crank case 9. A valve casing 11, common to all of the cylinders, extends along the upper ends of the same and is shown as arranged centrally of the diameter of the cylinders and made integral with the heads of the several cylinders. Said valve casing 11 is provided with a cylindric valve chamber, extending transversely of, and common to all of said cylinders. A cylindric valve member 12 has bearing in said chamber, and is adapted to turn or rotate therein.

Along one side of the valve casing 11 extends an admission pipe 13, forming a passage through which the explosive mixture is delivered to the upper ends of the several cylinders, the same being shown as provided, centrally of its length, with an admission opening 13^a. At the opposite side of the valve casing a pipe 14 extends along the same; said pipe constituting a passage through which the waste gases are exhausted, and which is shown as provided with a central exhaust pipe 14^a.

While the valve member 12 is shown as made in one piece and as extending across the ends of all of the cylinders, yet said valve member consists, in effect, of four connected sections, one for each cylinder. As all of said sections are alike, except for the different circumferential location of the parts thereof necessary for the successive operation of the several cylinders, as are also the features of and upon the valve casing associated with each of said cylinders and sections, the parts associated with each of the several cylinders are correspondingly lettered, in the drawings, and those associated with one cylinder only need be described.

In connection with each main cylinder, the valve chamber is provided with two cylinder ports 15, 15^a, extending lengthwise of the valve casing and transversely of the cylinder head, and opening through said cylinder head into the interior of the cylinder. Said ports 15, 15^a are separated by a bridge 16 forming part of the cylinder head. The valve chamber is also provided at one side thereof with two admission ports 17, 17^a and at its opposite side with two exhaust ports 18, 18^a. The ports 17 and 17^a are arranged in line with each other longitudinally of the valve casing, as are also the exhaust ports 18 and 18^a. Said ports 17 and 17^a and 18 and 18^a are arranged circumferentially in alignment with the cylinder ports 15, 15^a. The supply ports 17 and 17^a are connected with the supply or inlet pipe 13, and the exhaust ports 18 and 18^a are similarly connected with the exhaust pipe 14. Two relatively long and narrow cylinder ports are used for each cylinder, in order to provide a maximum area of port

opening with a minimum extent of rotative movement in the valve member for opening and closing the same.

Each section of the valve member 12 is provided with two laterally facing recesses 21, 21^a extending part way around the valve member and in alignment with each other longitudinally of the valve member. The said recesses are located circumferentially in alignment with the cylinder admission and exhaust ports of the valve casing. The said recesses 21 and 21^a are adapted in the rotative movement of the valve member to bring the cylinder ports 15, 15^a alternately into communication with the inlet ports 17, 17^a and exhaust ports 18, 18^a, as common in the operation of rotative valves of this general character.

For giving rotative movement to the valve member 12, devices are provided as follows: On the crank shaft 10 of the engine, which extends outside of the crank case 9 at one end of the same, is mounted a beveled gear wheel 25 which intermeshes with a beveled gear wheel 26 attached to an upright shaft 27. On the upper end of said shaft is mounted a gear pinion 28 which meshes with a beveled gear wheel 29 secured upon a cylindric extension 12^a on the adjacent end of said valve member 12. The gear pinion 28 is so proportioned with relation to the gear wheel 29, that the valve member 12 is given one complete rotation during two rotations of the crank shaft, as common in engines of this character. Said shaft 27 is shown as consisting of three sections 27^a, 27^b and 27^c, which are connected to each other by means of universal joints 28^a, 28^b, formed in a familiar manner by means of short sleeves 28^c joined to the shaft sections by pairs of transverse pivot members 28^d, arranged at right angles to each other. The upper shaft section 27^c is mounted in a bearing 30^a secured to the upper end of an upright standard 30 which, at its lower end, has loose or sliding connection with the crank case 9. Attached to or made integral with the top of the bearing 30^a is a gear case 31 which incloses the gears 28 and 29, and is provided with a sleeve 32, which surrounds or through which extends the cylindric extension 12^a of the valve member 12. Between the said extension 12^a and the sleeve 32 is located a cylindric bushing 33 (Fig. 3) within which the said extension 12^a directly turns or rotates. The special features of construction in the shaft 27, standard 30 and the gear case 31, which is engaged with the end of the valve member 12, as described, is designed to permit endwise shifting movement of the valve member in the valve chamber, for a purpose not forming a part of this invention.

In the top wall of the valve casing, between the inlet ports 17 and 17^a and the ex-

haust ports 18 and 18^a is formed a longitudinally extending slot or opening, preferably made of the same width as the diameter of the valve member 12, and within said opening is located a movable or sliding block 35, having parallel side faces adapted for sliding engagement with the parallel side faces of the said opening. Said block 35 is shown in the drawings as extending throughout the entire length of the valve casing and valve member, although, in effect, consisting of a plurality of sections, each of which operates in connection with one of the parts or sections of the said valve member, severally associated with the engine cylinders. Said block 35 has a concave inner face which conforms to and bears against the cylindric surface of the valve member 12 at the side of the same opposite the part of the valve seat containing the cylinder ports 15 and 15^a. Said block 35 is so arranged in connection with the valve member 12 that when it is pressed downwardly or inwardly toward and against the valve member, it acts to press or hold the latter against the part of its seat in which the cylinder ports are formed.

While in the multi-cylinder engine illustrated, the valve member 12 and the block 35 are shown as each made of a single piece, extending the full length of the valve casing, yet, if desired, the several sections of the valve member may be so joined at their ends as to turn or rotate together otherwise than by being made integral with each other, while the sections of the block 35 need not necessarily be united or joined to each other, and may be separately movable in the valve casing. Devices, operated through the action or pressure of fluid within the cylinder, are employed for pressing or forcing said movable block 35 toward the valve member 12. Separate devices for this purpose are provided in connection with each of the cylinders and are adapted to operate upon the part or section of the longitudinally extending block 35, associated with each cylinder. Such devices, as shown in the principal figures of the drawings, are constructed as follows: Such devices, as clearly seen in Fig. 4, embrace an auxiliary cylinder 36 closed at one end and provided at its closed end with a passage 37 communicating with the interior of the cylinder, a piston 38 in said cylinder 36, a piston rod 39 attached to said piston, a lever 40 which is mounted upon a pivot or fulcrum 41 secured to the valve casing, and a lever 42 connected at one end to the valve casing and at its opposite end to the lever 40, said lever 42 being arranged to extend over the upper or outer face of the block 35 and having bearing engagement with said block. These parts are so arranged that the fluid under pressure within the cylinder, entering the

auxiliary cylinder 36 through the opening 37, acts on the piston 38, and the pressure exerted on said piston through the medium of the connecting devices described acts upon the upper or outer face of the block 35 to press said block against the valve member 12 and to thereby exert a pressure on said valve member in opposition to the pressure exerted on said valve member through cylinder ports from the interior of the cylinder, and tending to lift said valve member from the part of its seat in which the cylinder port is formed.

Referring to the details of construction in the parts last referred to, the auxiliary cylinder 36 is shown as formed in a lateral extension of the cylinder head, below the admission pipe 13, and as arranged to open at its upper end into said inlet pipe. In vertical alignment with the cylinder 36, said inlet pipe is provided with a circular aperture 13^a, provided with a removable closure or disk 43, having a central guide opening through which the upper end of the piston rod 39 extends. The diameter of the opening 13^a is made larger than the diameter of the cylinder 36 so that when the disk 43 is detached the piston 38 may be removed or inserted through said opening. The fulcrum pin 41 of the lever 40 is secured at its ends by bolts 41^a to the top of the valve casing. The end of the horizontal lever 42 adjacent the lever 40 is arranged in overlapping relation to the adjacent end of said lever 40 and is connected therewith by means of a bolt 44 extending through vertically aligned apertures in the levers 40 and 42. Said bolt 44 has at its lower end a transverse cylindric head 44^a, which bears against seats formed in the lower surface of the lever 40 at the sides of the bolt, and at its upper end a nut 44^b applied to the screw-threaded end of said bolt above the lever 42. The said lever 42 is held from movement relatively to the valve casing by a fulcrum connection consisting of a bolt 45, inserted through an aperture in said lever, secured at its lower end in the valve casing and provided with a nut 45^a which bears on the top of the lever. The said bolt 45 is loosely fitted in the aperture of the lever 42 in order to permit the slight degree of movement required in the said lever. The said lever 42 is adapted to bear on the block 35 at the center line of the same; said lever being provided with oppositely extending rigid arms 42^a, 42^b, each provided at its end with a depending projection 42^c for contact with the top surface of said block.

In the construction described, it will be understood that the concave bearing face of the block 35 rests in contact with the cylindric surface of the valve member 12, and that, upon any increase of the pressure of the fluid within the cylinder, such as will

take place upon the ignition of the explosive charge in the internal combustion engine shown in the drawing, the pressure exerted by such fluid on the piston 38 will be transmitted therefrom to the outer or upper face of the block 35 and, acting through said block on the valve member, will press or hold the same in contact with the part of the inner surface or seat of the 5 valve chamber adjacent to the cylinder ports, and will, therefore, operate to counteract or oppose the pressure of the fluid in the cylinder acting on the valve member through the cylinder ports, and tending to 10 lift the valve member from contact with the part of its seat in which such ports are formed. It follows that an increased pressure in the cylinder will be accompanied by an increased pressure of the valve member 15 upon the part of its seat adjacent to or surrounding the cylinder port, thereby greatly lessening the liability of leakage of the fluid from the cylinder port to either the inlet or exhaust ports of the valve chamber. Moreover, the construction described insures 20 close contact of the valve member with the part of its seat adjacent to the cylinder ports regardless of wear in the parts.

As an improvement in rotative valves of the general character illustrated, I have provided the valve casing with vents or openings 47, 47 extending through the wall of the valve casing at the side of the same opposite the cylinder ports 15, 15^a, and in 25 the construction illustrated, formed in the movable block 35. Said vent openings open at their inner ends through the cylindric bearing surface of the valve chamber at points circumferentially in line with the recesses 21, 21^a of the valve member, and are so arranged that when, in the rotation of the valve, the rear margins of said recesses have been carried past the cylinder ports and said recesses are still in communication 30 with the inlet ports 17, 17^a, the forward edges of said recesses will have moved past the said vent openings and the latter will be in communication with said recesses. The partial vacuum exerting in the inlet 35 passage of the engine, by reason of the action of one or more of the pistons in the several cylinders, in the charging or suction strokes thereof, will result in air being drawn inwardly through said vent openings and into the said recesses, thereby displacing the part of the explosive charge which will remain therein as a result of the suction stroke of the piston in the associated cylinder; the explosive mixture thus 40 placed being drawn into or escaping to the said inlet passage. By the use of such vent openings, therefore, the carrying of the parts of the explosive charge from the inlet to the exhaust ports, and consequent loss

of a part of the explosive charge at each 45 rotation of the valve member is largely avoided.

In Figs. 8, 9 and 10, I have shown details of construction in the piston 38, designed to provide a packing for said piston adapted to always maintain a tight or close joint between the piston and the cylinder 50 36. As shown in these figures, the said piston is provided between its ends with an annular groove within which is inserted a split or expansible metal ring 70. In the body of the piston and opening into said annular groove are formed two radial recesses 71, 71, in which are placed two coiled springs 72, 72 adapted 55 to bear upon the part of the split ring 70 diametrically opposite the split or severed ends of the same. Said springs 72, 72, thus arranged, tend to press the portion of the split ring opposite its severed ends against 60 the adjacent side of the wall of the cylinder and at the same time to press or hold the side of the piston itself, at which the severed ends of the ring are located, in constant contact with the cylinder wall. As 65 a result of this construction in the piston, the portion of the side surface of the piston, adjacent to the severed ends of the ring, is always maintained flush with the outer surface of the ring at the ends of the 70 same, and the surfaces of the piston, above and below the slit or opening between the severed ends of the ring serve to close, and to prevent leakage through, such slit or opening. It will of course be understood 75 that the contact of the ring with the interior of the cylinder in parts elsewhere than at its ends, will always serve to maintain a tight joint between the piston and the cylinder, notwithstanding the fact that 80 the piston itself is pressed toward or against one side of the cylinder, as stated. In the details of construction shown, said piston 38 is provided at its inner end with a permanently attached disk 38^a, the margin of which forms one side of the groove in the piston, and bears against one edge of the split ring 70. Said disk is centrally apertured and held centrally on the piston by fitting over a cylindric, integral stud 85^b on the body of the piston; screws 38^c being inserted through the disk 38^a and into the body of the piston to hold said disk in place. The disk 38^a is detachably secured to the body of the piston in order to enable 90 the packing ring 70 to be easily applied to and removed from said piston. In addition to the springs 72, 72, the piston is shown as provided with a third, like spring 73 inserted in a radial recess 74 and adapted 95 to bear outwardly against both of the severed ends of the ring. Said spring 73, thus arranged, serves to insure that the said

severed ends of the ring shall be always pressed outwardly against the wall of the cylinder. In order to insure the operation of the packing ring, as hereinbefore stated, it is necessary that the side of the ring opposite its severed ends should be pressed against the side of the cylinder with a greater force than that exerted by the spring 73, when the latter is used. For this reason, I have shown two springs 72, 72 arranged to act in opposition to the spring 73, but it will be understood that the greater pressure on the side of the ring opposite its severed ends may be obtained otherwise than by employing the two springs illustrated. A pin 75 is shown as inserted in the body of the piston and engaged at its outer end with a hole or recess in the ring, so as to prevent rotative movement of the latter on the piston and maintain the severed ends of the ring always in proper relation to the springs 72 and 73. The said piston 83 is preferably provided with an annular groove 76 (Fig. 8), and the wall of the cylinder with a small aperture or vent opening 76^a, the inner end of which opens into said groove. Said groove and vent opening are employed in order that any of the burning gases or the products 30 of combustion, from within the main cylinder, that may leak past the piston packing, will escape to the outer air and thus be prevented from entering the main inlet passage 13; this being a feature especially 35 applicable to the particular construction shown, wherein the cylinder 36 opens at its upper end into said inlet passage.

In Figs. 11, 12 and 13 I have illustrated another form of construction in means by 40 which the movable bearing block 35 may be pressed toward or held in contact with the rotative valve member 12. In this instance a plate 80 is rigidly attached by bolts 81, 81 to the top of the valve easing and extends over or across the outer face of said block 35. Said plate 80 is provided with an internal cylindric recess or chamber 82 forming, in effect, a short or shallow cylinder. In said recess 82 is located a piston 50 83 which rests or bears against the adjacent face of the block 35. A port or passage 86 extends from the top of the main cylinder upwardly through the valve easing and is connected at its upper end with a 55 passage 86^a in the plate 80; said passage 86^a communicating with the space at the top of the recess 82 above the piston 83. Said piston 83 may be provided with a packing ring constructed in the same manner as 60 hereinbefore described in connection with Figs. 8, 9 and 10.

In the operation of the device shown in Figs. 11, 12 and 13, the fluid held under pressure within the main cylinder acts on

the outer face of the piston 83 to press the 65 same against the block 35, and thereby presses said block against the cylindric valve member and the latter toward the part of its seat in which is formed the cylinder ports. As shown in said Figs. 11 and 13, the plate 70 80 is provided with laterally projecting parts 80^a, 80^b, in which are mounted vertically movable plungers 87, which bear upon the outer face of the block 35 at the longitudinal center line of the same, through the 75 action on said plungers of coiled springs 88. The employment of an auxiliary spring actuated, pressing device acting to press constantly on the outer face of the block 35, has the advantage of insuring constant pressure of said block against the valve member 80 at times when there is no pressure in the main cylinder; thereby preventing any outward movement of the block and valve member at such times, as for instance, during 85 the charging or suction stroke of the piston of an internal combustion engine. Such auxiliary pressing device, moreover, may be employed with advantage in the construction shown in the principal figures of the 90 drawings, as well as in the form of construction shown in Figs. 11 to 13.

Figs. 14 and 15 illustrate still another construction in means adapted to afford an inward pressure against the movable block 95 35. In this instance the construction is generally like that shown in Figs. 11 to 13, with the exception that a flexible diaphragm is used in place of the piston 83, as shown in Fig. 12. A circular plate 91 is, 100 in this instance, connected by bolts 92, 92 to the top of the valve easing, at opposite sides of and extending across the outer face of the said block. A flexible diaphragm 90 is attached at its margins to the bottom or 105 inner surface of the plate 91 and extends over or closes a shallow recess formed in the inner face of the said plate. In communication with said recess is a passage or port 93 leading from the interior of the main 110 cylinder. The pressure within the main cylinder is exerted on the outer face of the diaphragm 90 and the latter is thereby pressed against the block 35, with the same 115 result as hereinbefore stated. As a preferred construction the plate 91 is provided with a screw-threaded aperture which is closed by a removable plug 94 having screw-threaded engagement with the plate. The plate is provided with such removable plug 120 in order to afford access to the recess therein, above the diaphragm 90, for the purpose of removing any solid material which may there accumulate because of the fact that the products of combustion from within the 125 cylinder enter the said recess. It will be observed that the movable block 35 which has bearing against the cylindric valve mem-

ber, as described, is located in a longitudinal slot or opening in the valve casing, which slot or opening extends through the outer face of said casing, and that said valve casing is provided with a member or members, detachably secured thereto at opposite sides of said opening and extending across the outer face of the movable block; said member or members constituting a medium through which pressure is transmitted to the said block. In the construction shown in Figs. 1 to 6, the member which is detachably connected with the valve casing has the form of the lever 42 through which pressure is transmitted, from the piston in the auxiliary cylinder to the said block, while in the construction shown in Figs. 12 and 13, the said member consists of the plate 90, which contains the auxiliary cylinder and piston, while in the construction shown in Figs. 14 and 15, the said member consists of the plate 91 carrying the flexible diaphragm and having a space above the same to which fluid under pressure is admitted. In all of the forms of construction described, embracing an outwardly opening recess for the bearing block and a member detachably secured to the valve casing and extending over the outer face of said block, by detaching said member the block may be removed and the cylindric valve member taken out of the valve casing. It follows that the features of construction referred to embracing the outwardly opening recess in the valve casing in which the movable block is located and a removable member extending over the outer face of the block and through the medium of which pressure is transmitted to the said movable block, afford the great advantage of enabling the valve chamber to be opened and the cylindric valve member removed therefrom, for inspection or repairs, by the expenditure of only a small amount of time and with little trouble.

It will be understood that a principal feature of my invention is embraced in a construction, in connection with a valve seat and a movable valve member, whereby the pressure exerted on the valve member in a direction to lift or separate it from its seat is counterbalanced or counteracted by pressure, on the side of the movable valve member opposite said seat, derived from the cylinder or other space with which the port controlled by the valve communicates, and acting on the valve member through the medium of a pressure or bearing block and mechanically operating pressure transmitting means and that, as the term "cylinder" is used in the appended claims, the same is intended to mean any space or enclosure which may contain a fluid under pressure, acting on the movable valve member, through the port controlled by the valve, and tending to lift the latter from its seat.

It will also be understood that the means shown in Figs. 12 to 15 of the drawings for transmitting pressure from the interior of the cylinder to the outer face of said pressure block are not herein claimed as part of my present invention, which, so far as such means for transmitting pressure is concerned, has for its subject matter mechanically operating pressure transmitting means, interposed between a piston or like member, which is subject to the pressure within the cylinder, and the said bearing block, and acting on said block in a direction to press the same toward the valve member. It will be further understood that the mechanism may be so proportioned that the counterbalancing pressure applied to the valve will be slightly in excess of the pressure tending to lift it from its seat or the counteracting pressure may be substantially equal to that tending to lift it from its seat, and springs such as those illustrated, may be used to give the excess pressure needed to insure the constant seating of the valve.

While the principal features of my invention may be employed in connection with valves of many kinds or forms, the same afford special advantages in connection with a valve having a cylindric valve chamber and a cylindric valve member therein. Valves of this general type have important advantages, by reason of the simplicity of construction and certainty of operation thereof, but they have not heretofore been generally used because of the inefficient character and complicated construction of devices heretofore used in connection with valves of this kind, for compensating for wear and preventing leakage.

By my improved features of construction, the cylindric valve member will always have close and accurate bearing on its seat, regardless of wear on the parts, and without the use of special packing devices or other features tending to make the construction complicated, expensive and lacking in durability.

My invention has special advantage in connection with multi-cylinder engines of the internal combustion type, wherein it is necessary that the valve seats of the several cylinders shall retain their shape and remain in alignment with each other, notwithstanding the wear on the parts.

A special advantage of applicant's construction in the valve casing and bearing block, in connection with a multi-cylinder engine, is that such construction enables the valve casing to be easily opened and the valve removed, to afford access to the seats and parts of the several valves. The features referred to, moreover, enable a very simple construction to be provided in the ports or passages of the valve casing and cylindric valve member, while permitting

such ports and passages to be easily made of any desired area, according to the requirements of any special engine.

The rotative valve member illustrated in 5 the drawings is shown as made hollow or tubular, although this construction is not essential. The use of a hollow or tubular valve member is preferred, however, because of its lightness and also for the reason that, 10 where the sections thereof, associated with the several cylinders, are made continuous with each other, the hollow form of valve gives such degree of flexibility in the valve member as a whole as to permit the different sections thereof to be easily and with certainty held against their several seats.

While I have shown in the accompanying drawings, an engine embodying the preferred form of my invention, yet it is to be 20 understood that the details and features of construction thereof may be variously modified in practice without departure from the spirit of my invention, and I do not desire to be limited to the specific features of construction illustrated, except so far as the same may be herein claimed as part of my invention.

I claim as my invention—

1. The combination with a cylinder, of a 30 valve embracing a valve casing having a valve seat and a port in said seat communicating with the cylinder, a movable valve member coacting with said valve seat to open and close said port, a pressure block 35 acting on the side of the valve member, opposite the said port, a movable member located adjacent to, and subject to the pressure within, the said cylinder, and pressure transmitting means, interposed between 40 said movable member and said pressure block and acting on said block in a direction to oppose the pressure tending to lift the valve member from its said seat.

2. The combination with a cylinder, of a 45 valve embracing a valve casing having a valve seat and a port in said seat communicating with the cylinder, a movable valve member coacting with said valve seat, a pressure block acting on the side of said 50 valve member opposite said port, a movable member located adjacent to, and subject to the pressure within, the said cylinder, and means acting to transmit pressure from said 55 movable member to said pressure block, embracing a lever interposed between said movable member and said block.

3. The combination with a cylinder, of a 60 valve embracing a valve casing having a valve seat and a port in said seat communicating with the cylinder, a movable valve member in contact with said valve seat, a pressure block acting on said valve member on the side thereof opposite said valve seat, a movable member subject to the pressure 65 within the said cylinder, and power increas-

ing means operated by said movable member and acting to exert pressure on said pressure block in a direction to oppose the pressure tending to lift the valve from its said seat.

4. The combination with a cylinder, of a valve embracing a valve casing having a valve seat and a port in said seat communicating with the cylinder, a movable valve member in contact with said valve seat, a 70 movable pressure block coacting with said valve member on the side thereof opposite the valve seat, a movable member subject to the pressure within the said cylinder, and power increasing means including a lever 75 having a fixed fulcrum, operated by said movable member and acting to exert pressure on said pressure block in a direction to oppose the pressure tending to lift the valve member from its said seat.

5. The combination with a cylinder, of a valve embracing a valve casing having a valve seat and a port in said seat communicating with the cylinder, a movable valve member coacting with said valve seat, a 80 pressure block acting on said valve member in a direction to press the same toward said valve seat, an auxiliary cylinder located adjacent to and in open communication with the said cylinder, a piston in said auxiliary cylinder, and means embracing a lever, interposed between said piston and said pressure block, acting to transmit pressure from said piston to said block.

6. The combination with a cylinder, of a 85 valve embracing a valve casing having a valve seat and a port in said seat communicating with the cylinder, a movable valve member in contact with said valve seat, a pressure block acting on said valve member 90 in a direction to press the same toward said valve seat, an auxiliary cylinder located adjacent to and in open communication with the said cylinder, a piston in said auxiliary cylinder, and power increasing means operated by said piston and acting on said pressure block to press the same toward the valve member in opposition to the pressure tending to lift said valve member from its seat.

7. The combination with a cylinder, of a 100 valve embracing a valve casing having a valve seat and a port in said seat communicating with the cylinder, a movable valve member in contact with said valve seat, a pressure block acting on the valve member 105 in a direction to press the same toward said valve seat, an auxiliary cylinder located adjacent to and in open communication with the said cylinder, a piston in said auxiliary cylinder, and means acting to transmit pressure from said piston to said block, embracing a piston rod attached to the piston, and a lever connected with said piston rod and adapted to act on said block.

8. The combination with a cylinder, of a valve embracing a valve casing having a cylindric valve chamber, an elongated movable pressure block extending longitudinally of the valve chamber and forming a part of the wall of the same, a cylindric valve member in said valve chamber; the fixed part of said valve casing being provided with a concave valve seat and with a port in said valve seat in communication with the said cylinder, and the pressure block being substantially equal in length to the said valve seat and having a concave bearing surface in contact with said valve member, and means acting on said pressure block to press the same toward the valve member.
9. The combination with a cylinder, of a valve embracing a valve casing having a cylindric valve chamber, an elongated movable bearing block, forming a part of the wall of said valve chamber, and a cylindric valve member in said valve chamber, said valve casing being provided with a concave valve seat, and with a port in said seat communicating with the interior of the cylinder, the length of said bearing block being equal to that of the valve seat, and its width being not less than the diameter of the valve member, and said bearing block having a concave bearing surface in contact with said valve member, and means acting on said block to press the same toward the valve member.
10. The combination with a cylinder, of a valve embracing a valve casing having a cylindric valve chamber, an elongated, movable bearing block extending longitudinally of said valve chamber and forming a part of the wall of the same, a cylindric valve member in said valve chamber, the fixed part of said valve casing being provided with a semi-cylindric valve seat, constituting one-half of the bearing surface of the valve chamber and with a port in said seat communicating with the interior of the cylinder, and said movable bearing block being provided with a semi-cylindric bearing surface, constituting the other half of the bearing surface of said valve chamber, and means acting on said block to press the same toward the valve member.
11. The combination with a cylinder, of a valve embracing a valve casing having a cylindric valve chamber, an elongated, movable bearing block forming a part of the wall of said valve chamber, and a cylindric valve member in said valve chamber, the fixed part of said valve casing being provided with a concave valve seat, with a port in said seat communicating with the interior of the cylinder, and with parallel, inwardly facing bearing surfaces, located exterior to the said semi-cylindric seat, and said bearing block having side faces in contact with
- said parallel surface of the valve casing, and being provided with a concave bearing surface, in contact with the valve member, and the length of said bearing block being substantially equal to that of the valve seat, and means acting on said block to press the same toward the valve member.
12. The combination with a cylinder, of a valve embracing a valve casing having a cylindric valve chamber, a cylindric valve member in said valve chamber, the fixed part of the valve chamber being provided with a concave valve seat, with a port in said seat communicating with the interior of the cylinder, and with an opening extending lengthwise of the valve seat and the full length of the valve casing and also extending through the outer surface of said valve casing, an elongated, movable bearing block forming a part of the wall of said valve chamber, and located in said opening extending lengthwise of the valve slot, said bearing block corresponding in length and width with said opening and having a concave bearing surface in contact with the valve member, and means acting on said bearing block to press the same toward the valve member.
13. The combination with a cylinder, of a valve embracing a valve casing having a cylindric valve chamber, an elongated, movable pressure block extending longitudinally of the valve chamber and forming a part of the wall of the same, a cylindric valve member in said valve chamber; the fixed part of said valve casing being provided with a concave valve seat and with a port in said valve seat in communication with the said cylinder, and the pressure block being substantially equal in length to the said valve seat and having a concave bearing surface in contact with said valve member, an auxiliary cylinder in open communication with the said cylinder, a piston in said auxiliary cylinder, and means for transmitting pressure from said piston to said block, acting to press the said block toward the valve member in opposition to the pressure tending to lift said valve member from its seat.
14. The combination with a cylinder, of a supply passage, a valve embracing a valve casing provided with a valve seat, and with a port in said seat communicating with the interior of the cylinder, a valve member co-acting with said valve seat, a pressure block acting on said valve member to press the same toward said valve seat, an auxiliary cylinder opening at one end into the said supply passage and in open communication at its opposite end with the cylinder, a piston in said auxiliary cylinder, and means for transmitting pressure from said piston to the said pressure block in opposition to the pressure tending to lift the valve member from its seat.

15. The combination with a cylinder, of a valve embracing a valve seat provided with a port communicating with the interior of the cylinder, a valve member having bearing on said seat, a movable block adapted to bear upon the side of said valve member opposite said port, and surrounding a portion of said valve member, means subject to the pressure within the cylinder connected with said movable block and acting to press the same toward the valve member, and auxiliary pressing means embracing a spring acting on said block to press the same toward the valve member. 40
- 5 16. The combination with a cylinder, of a valve embracing a valve casing, provided with a valve seat and with a port in said valve seat communicating with the interior 45
- 10 of the cylinder, a valve member having bearing on said seat, a movable block adapted to bear on the side of the valve member opposite said seat, an auxiliary cylinder in open communication with the cylinder, a piston 50
- 15 in said auxiliary cylinder provided with a piston rod, a lever having its fulcrum on the valve casing at one side of said block and extending across the outer face of the block, a second lever fulcrumed between its ends 55
- 20 on the valve casing, and a connecting rod uniting the movable end of the first named lever with one end of the second named lever, said piston rod being adapted to act upon the opposite end of said second named lever. 60
- 25 17. The combination with a cylinder, of a valve embracing a valve seat provided
- 30 with a port communicating with the interior of the cylinder, a valve member having bearing on said seat, a movable block adapted to bear upon the side of said valve member opposite said port, and surrounding a portion of said valve member, means subject to the pressure within the cylinder connected with said movable block and acting to press the same toward the valve member. 65
- 35 18. The combination with a cylinder, of a valve embracing a valve casing provided with a cylindric valve chamber and with a port in said chamber communicating with the interior of the cylinder, a cylindric valve member having bearing in said chamber, a movable block having a bearing surface which forms part of the cylindric bearing surface of the valve chamber and is adapted to bear upon the side of the valve member opposite said port, an auxiliary cylinder in open communication with the end of the cylinder, a piston in said auxiliary cylinder, operative connections between said piston and said block, and auxiliary pressing means comprising a spring applied to act on the outer face of the said block. 70

In testimony that I claim the foregoing as my invention I affix my signature in the presence of two witnesses, this 30th day of Nov. A. D. 1912.

WILLIAM HENRY FAUBER.
